UNITED STATES PATENT OFFICE.

FERDINAND GAILER, OF NEW YORK, N. Y.

BOOK-SEWING MACHINE.

1,153,775.

Specification of Letters Patent. Patented Sept. 14, 1915.

Application filed July 17, 1913. Serial No. 779,498.

To all whom it may concern:

Be it known that I, FERDINAND GAILER, a citizen of the United States, and a resident of the city of New York, borough of Manhattan, in the county and State of New York, have invented a new and Improved Book-Sewing Machine, of which the following is a full, clear, and exact description.

The object of the invention is to provide a new and improved book sewing machine for sewing signatures and fly leaves or linings together in a very simple and effective manner and without requiring the employment of highly skilled labor.

In order to accomplish the desired result use is made of a reciprocating sewing needle, a stitch-forming mechanism operating in conjunction with the said sewing machine needle, and a signature carrier for holding superimposed signatures and for feeding the same step by step under said sewing needle to pass slantingly through the uppermost signatures to the back thereof and to then form stitches with the said stitch-forming mechanism at the backs of the signatures. Use is also made of a presser foot capable of working on top of the uppermost signature or between the lining and the first and last signatures when uppermost, and in order to insure a positive formation of the stitch use is made of a needle guide to cause the stitch-forming mechanism to take the loop at each descent of the sewing needle.

A practical embodiment of the invention is represented in the accompanying drawings forming a part of this specification, in which similar characters of reference indicate corresponding parts in all the views.

Figure 1 is a front elevation of the book sewing machine; Fig. 2 is a plan view of the same; Fig. 3 is a side elevation of the same with the signature carrier removed; Fig. 4 is an enlarged front face view of the needle guide; Fig. 5 is a rear face view of the same; Fig. 6 is a sectional side elevation of the same on the line 6-6 of Fig. 5; Fig. 7 is a plan view of the same on the line 7-7 of Fig. 6; Fig. 8 is a front elevation of the superimposed signatures with the lining in position thereon and with the needle in lowermost position extending through the lining and the uppermost signature, the latter being engaged by the presser foot and by the top clamping bar of the signature carrier, the top clamping bar being shown in section; Fig. 9 is an enlarged sectional side

elevation of the book sewing machine on the line 9-9 of Fig. 10; Fig. 10 is a plan view of the same with parts in section on the line 10-10 of Fig. 9; Fig. 11 is a plan view of the spring presser foot; Fig. 12 is a transverse section of the signature carrier in position on the bottom of the guideway, the section being on the line 12-12 of Fig. 1; Fig. 13 is a sectional plan view of the same on the line 13-13 of Fig. 12; Fig. 14 is a rear face view of the needle support in section; and Fig. 15 is an enlarged side elevation of the locking device for temporarily locking the signature carrier in step by step position on the bottom of the guideway.

The book sewing machine is mounted on a suitably constructed stand A on the top of which is secured the base B' of a sewing machine B of any approved construction, it being deemed sufficient to state that the sewing machine is provided with a vertical reciprocating needle C and a stitch-forming mechanism D operating in conjunction with the sewing needle C in the usual manner for forming the stitches so that further description of the same is not deemed necessary.

The properly assembled signatures E forming a book are superimposed and clamped in this position on a signature carrier F mounted to slide transversely on a guideway G attached to the stand A. The signatures F are supported in such a manner that their backs are at an angle to the path of the sewing needle C so that the latter passes slantingly through, at least, the two uppermost signatures E to carry the sewing thread down through the back of the signatures to be looped with the shuttle thread (not shown) by the stitch-forming mechanism B to complete the stitches at the backs of the signatures a distance below the uppermost signature, as will be readily understood by reference to Fig. 9.

In case the signatures E are of heavy paper it is desirable to provide an easy passage of the sewing needle C through the uppermost signatures as described, and for this purpose use is made of a hole punch I (see Figs. 3 and 14) arranged a distance in front of the sewing needle C (say half an inch) and reciprocating with the same to punch a slanting hole in the uppermost signatures for the subsequent passage of the sewing needle C on feeding the carrier F rearwardly a distance corresponding to the distance between the sewing needle C and the

hole punch I. The hole punch I is removably attached to a bar I' secured at its lower and upper ends to the needle bar C' of the sewing machine, see Fig. 14.

- 5 The guideway G is constructed as follows: A ledge G' is secured to the stand A with its face at an angle to the sewing needle C, as plainly indicated in Fig. 9, and from the face of the ledge G' extends at a right angle 10 a supporting plate or bottom G² provided with nuts G³ extending through slots G⁴ formed in the ledge G' to guide the bottom G² when moved up or down on the ledge G'. In the nuts G³ screw screw rods J journaled 15 in suitable bearings arranged on the under side of the ledge G', and the lower ends of the screw rods J are provided with gear wheels J' in mesh with bevel gear wheels J² secured on a transverse shaft J³ journaled in 20 suitable bearings arranged on the back of the ledge G'. The front end of the shaft J³ is provided with a hand wheel J⁴ (see Fig. 1) under the control of the operator to permit the latter to turn the shaft J³ with a 25 view to rotate the screw rod J to move the bottom G² upward or downward according to the direction in which the hand wheel J⁴ is turned. By the arrangement described the bottom G² can be minutely adjusted up 30 or down to suit the aggregate thicknesses of the superimposed signatures E to be sewed together at the time. It is understood that the uppermost signature must always be immediately below the point of the sewing 35 needle C at the time the latter is in its uppermost position, so that the carrier F can be shifted transversely and the needle point on the descent of the sewing needle passes through several of the uppermost signatures 40 in order to finally reach the stitch-forming mechanism D. The outer portion of the bottom G² is provided at the under side with a bearing G⁵ engaged by an angular lug K held on the upper end of a screw rod K' 45 screwing in the upper end of a turn buckle K², in the lower end of which screws a screw rod K³ forming an angular lug K⁴ engaging a bearing K⁵ attached to the upper end of a standard A' forming part of the stand 50 A. When the bottom G² is adjusted up or down the turn buckle K² is turned correspondingly so as to provide a suitable support for the outer end of the bottom G² to hold the latter steady while moving the signature carrier F transversely on the top of 55 the bottom G².
- The upper surface of the bottom G² of the guideway G is provided with transversely-extending rails G⁶ on which travel 60 rollers F' to permit easy transverse moving of the signature carrier F. On the bottom F² are arranged superimposed filling pieces or plates F³ on the uppermost of which rests the lowermost signature E, it being understood that the backs of the signatures E as

well as the filling pieces F³ abut against the face of the ledge G' so as to hold the signatures at an angle to the sewing needle C.

In order to clamp the superimposed signatures E in position on the uppermost filling piece F³ of the carrier F, use is made of a clamping plate F⁴ attached to the underside of a cross bar F⁵ loosely guided on upright pins F⁶ (see Fig. 12) attached to the front and rear ends of the bottom F² of the carrier F. A spring F⁷ is coiled on each of the rods F⁶ and is interposed between the bottom F² and the bar F⁵ to normally hold the bar F⁵ raised and with it the clamping plate F⁴ to allow convenient changing of the position of the signatures E, as hereinafter more fully described.

In order to move the clamping plate F⁴ into clamping engagement with the uppermost signature, use is made of eccentric cams L secured on the shaft L' journaled at its ends in bearings L² vertically slidable on the pins F⁶ and secured against upward movement by locking pins L³, each extending through one of a series of openings in the corresponding pin F⁶. On the shaft L' is secured a handle L⁴ under the control of the operator for turning the cam shaft L' with a view to cause the cams L to move the bar F⁵ downward to engage the clamping plate F⁴ with an uppermost signature to clamp the signatures in place on the carrier F. When the handle L⁴ is swung upward the cams L release the bar F⁵ so that the latter is caused to move upward by the action of the springs F⁷ to lift the clamping plate F⁴ off the uppermost signature to permit the operator to change the positions of the signatures.

The signature carrier F with the signatures E clamped thereon is moved transversely by the operator, and in order to provide a step by step movement with a view to space the stitches equal distances apart use is made of the following device: On the upper face of the bottom G² and at the outer end thereof is arranged a transversely-extending bar G⁷ provided with notches G⁸ spaced equal distances apart corresponding to the distance between the sewing needle C and the punch I, and the said notches G⁸ are adapted to be engaged by a lug N (see Fig. 15) formed on the free end of the lever N' fulcrumed at N² on a plate N³ secured to the bottom F² of the signature carrier F (see Figs. 1, 2, 9, 10 and 15). The lever N' is provided with a finger piece N⁴ adapted to be pressed by the operator to swing the lug N out of engagement with a notch G⁸, and the said lever N' is pressed on by a spring N⁶ held on the plate N³ and adapted to hold the lug N normally in engagement with a corresponding notch G⁸. On the plate N³ is pivoted a locking catch N⁵ adapted to be swung into engagement with the finger piece N⁴.

N^4 at the time the latter is pressed downward so as to lock the lever N' in position with the lug N raised and out of engagement with the corresponding notch G^8 . Normally 5 the lever N' is unlocked and the lug N is in engagement with a notch G^8 to hold the signature carrier F against transverse movement, and after a stitch is completed the operator presses the finger piece N^4 to unlock 10 the signature carrier F . When this has been done, the operator pushes the signature carrier F rearwardly until the lug N snaps into the next notch G^8 preparatory to actuating the sewing machine for making another 15 stitch.

On the front end of the bottom F^2 of the signature carrier F is mounted a gage O for the front ends of the filling pieces F^3 , and the signatures E to abut against (see Figs. 20 1, 2, 12 and 13). The gage O is provided with an angular base plate O' resting on the upper surface of the bottom F^2 , and the said base plate O' is provided with guide slots O^2 engaged by screws O^3 screwing in the bottom F^2 to slidably hold the gage O in position 25 on the signature carrier F . The lever P is fulcrumed at P' on the bottom F^2 and is arranged on top of the base O' , and the said lever is provided with a pin P^2 engaging a slot O^4 formed in the base O' . The pivot P' extends through the slot O^4 and is adapted to pass through a slot O^5 arranged parallel to the slots O^2 . Now on imparting a swinging motion to the lever P in the direction of 30 the arrow a' , shown in Fig. 13, a sliding motion from forward to rearward is given to the gage O to shift the latter a distance corresponding to one-half the distance between adjacent stitches. In a like manner when 35 the lever P is returned from the position shown in dotted lines in Fig. 13 to the position shown in full lines in said figure, then the gage O is moved back the same distance, and the operator now shifts the filling 40 plates F^3 and the signatures E toward the front until they abut against the gage O so that the next row of stitches will be intermediate the previous row of stitches.

A presser foot Q bears down on the uppermost signature adjacent the sewing needle C at the time the latter descends and passes through the hole previously made by the punch I . The presser foot Q is in the form of a spring secured at its right-hand end to 50 a block Q' attached to the base B' of the sewing machine, and the free end of the presser foot Q is provided with a recess Q^2 (see Fig. 11) for the passage of the sewing needle C . An arm Q^3 bears on the presser foot Q near the free end thereof and this arm Q^3 is secured to a plate Q^4 slidably engaging guideways R provided with trunnions R' journaled in bearings R^2 attached to the base B' of the sewing machine B. 55 The plate Q^4 is provided with a slot Q^5 engaged by a clamping bolt R^3 held on a connecting plate R^4 connecting the guideways R with each other. By this arrangement the plate Q^4 is adjustably secured in position on the guideways R . In order to cause the arm 70 Q^3 to bend the presser foot downward into engagement with the uppermost signature E use is made of a lever S engaging the under side of the connecting plate R^4 of the guideways R , as plainly shown in Fig. 9. The lever S is fulcrumed at S' on the base B' of the sewing machine and is connected with a spring S^2 attached to the overhanging arm of the sewing machine to normally hold the lever S out of position with the connecting 75 plate R^4 . The lever S is also connected by a link S^3 with a treadle S^4 under the control of the operator and fulcrumed on the lower portion of the stand A. When it is desired to cause the presser foot to bear down on 80 the uppermost signature E then the operator presses the treadle S^4 so as to cause the lever S to swing and thereby impart an upward swinging motion to the guideways R carrying the plate Q^4 and the arm Q^3 , whereby the latter bears down on the presser foot Q and bends the same downward into firm contact with the uppermost signature. This is done immediately prior to the descent of 85 the sewing needle C , and after the sewing 90 needle C has made its full stroke and formed a stitch with the stitch-forming mechanism D and returned to uppermost position, then the operator releases the treadle S^4 to allow the spring S^2 to return the lever S to normal 95 inactive position, whereby the presser foot Q by its own resiliency swings upward out of engagement with the uppermost signature E , thus releasing the same and allowing convenient shifting of the signature carrier F 100 for making the next stitch.

The sewing needle C during its descent passes through the opening in the needle plate T attached to the face of the ledge G' , as plainly indicated in Fig. 9. The needle 110 after passing through the needle plate T engages a needle guide U , shown in detail in Figs. 4, 5, 6 and 7. This needle guide U prevents the needle from bending in any direction, thus insuring a positive formation 115 of the stitch in conjunction with the stitch-forming mechanism D . The needle guide U is attached to the under side of the ledge G' and is provided at its upper end with an angular lug U' having an eye U^2 in register 120 with the opening in the needle plate T so that the needle C passes through the said eye U^2 and into a tubular groove U^3 formed in the needle guide U . A slit U^4 leads from the groove U^3 to the face of the needle 125 guide U opposite the stitch-forming mechanism D to allow the shuttle thread to pass through while forming the stitch with the sewing thread H . The slit U^4 is preferably 130 provided with downwardly-converging side

walls, as plainly indicated in Fig. 5, so as to provide sufficient room for the loop when the latter is drawn up by the tension devices of the sewing machine.

In order to support the sewing needle C above the signatures E use is made of a support V having an opening V' for the passage of the needle C, as plainly indicated in Fig. 14. The support V extends laterally from a bar V² mounted to slide vertically in a guideway B³ forming part of the head B⁴ of the sewing machine B. The bar V² is provided with a key V³ engaging a slot in the guideway B³ to hold the bar V² and consequently the support V from turning. The bar V² is provided with an upwardly-extending reduced portion V⁴ terminating in a head V⁵ mounted to slide in a bearing B⁵ arranged above the bearing B³ and forming part thereof. A spring V⁶ is coiled on the reduced portion V⁴ and rests with its lower end on the bottom of the guideway B³ and presses with its upper end on the head V⁵ to normally hold the support V in an uppermost position. The support V is a distance below the lower end of the needle bar C' at the time the latter is in uppermost position, and when the needle bar C' moves downward it finally engages the support V and carries the same along against the tension of the spring V⁶ so that the support V supports the sewing needle C above the uppermost signature to prevent wabbling of the needle during its passage through the uppermost signature.

On the rear of the head B⁴ of the sewing machine is arranged a cutting device preferably in the form of a pair of scissors W, one blade of which is provided with a dovetail tongue W' slidingly fitting a correspondingly shaped groove in a block W² attached to the rear end of the head B⁴ of the sewing machine. By the arrangement described the blade with the tongue W' is fixed and the other blade moves into open or closed position relative to the said fixed blade on the operator manipulating the handles correspondingly. The handles of the blades extend upwardly and the handle 50 of the fixed blade rests on a bracket W³ arranged on the head B⁴. The cutting device permits the operator to conveniently cut off the sewing thread H after a row of stitches has been made, as hereinafter more fully described.

As shown in the drawings, the sewing machine B is actuated by hand and for this purpose the main shaft B⁶ of the sewing machine is provided with a hand wheel B⁷ adapted to be turned by the operator, it being understood that one revolution of the shaft B⁶ causes a full down and up stroke of the sewing needle C to make a stitch in conjunction with the stitch-forming mechanism D. On the stand adjacent the hand

wheel B⁷ (see Fig. 2) is arranged a spring catch X adapted to engage a keeper X' held on the hand wheel B⁷ at the time the sewing needle C is in uppermost position to lock the sewing machine shaft B⁶ against accidental turning while shifting the signature carrier F, as hereinafter more fully explained. It is understood that sufficient power is exerted by the operator on the hand wheel B⁷ to disengage the spring catch X from the keeper X' to allow of turning the hand wheel B⁷ for making one stitch at a time.

The operation is as follows: When the sewing needle C is in uppermost position and the shaft B⁶ is temporarily locked against rotation by the catch X then the operator can conveniently slide the signature carrier F to the front of the guideway G so as to clear the needle C. The operator swings the handle L⁴ into an upward position to allow the clamping plate F⁴ to move upward by the action of the springs F⁷ with a view to permit the operator to place the superimposed signatures E in position on the top of the filling plates F³ and with the backs of the signatures abutting against the face of the ledge G'. When this has been done, the operator swings the lever L⁴ downward so as to clamp the signatures E in place by the clamping plate F⁴. The operator now pushes the signature carrier F rearwardly until the superimposed signatures are a short distance, say quarter of an inch, beyond the hole punch I, and then the operator unlocks the lever N' to engage the lug N with the corresponding notch G⁸. The operator next presses the treadle S⁴ so as to cause the presser foot Q to bear firmly down onto the upper surface of the uppermost signature adjacent the back thereof, as plainly indicated in Fig. 9. The operator now gives one revolution to the hand wheel B⁷ so that the hole punch I punches a slanting opening through the uppermost signatures. The operator now unlocks the lever N' by pressing the finger piece N⁴ downward and then the operator slides the signature carrier F rearward until the lug N drops into the next following notch G⁸ of the bar G'. The sewing needle C is now in register with the hole previously punched by the hole punch I. The operator now again actuates the treadle S⁴ to cause the presser foot Q to bear down on the uppermost signature adjacent the needle and then the operator gives another turn to the hand wheel B⁷ to cause the sewing needle C to descend in the hole previously made by the punch I and to form a stitch with the stitch-forming mechanism D and to draw the stitch taut on the backs of the signatures a distance below the uppermost signature. It is understood that during the downward and upward movement of the sewing needle C the hole punch I has

punched another hole slantingly through the uppermost signatures in front of the sewing needle. The operator next unlocks the signature carrier F and pushes the same rearward until the lug N engages the next following notch G⁸, after which the operator again actuates the treadle S⁴ and subsequently gives the hand wheel B⁷ one revolution to cause the sewing needle to pass downward through the second hole in the signatures and to form a stitch at the back of the said signatures the same as previously explained relative to the first stitch. The above-described operation is repeated until the several signatures are sewed together in the manner above mentioned. It is understood that prior to shifting the carrier F the operator releases the treadle S⁴ so as to allow the presser foot Q to move out of contact with the uppermost signature. In practice, the stitches are repeated at the first two holes at each end of the signatures. After the uppermost signatures have been sewed together, the operator moves the carrier F to the front clear of the sewing needle C, and then the operator swings the lever L⁴ upward into open position to raise the clamping plate F⁴. The operator now removes the lowermost signature from the pile of superimposed signatures and places the same on top, after which the lever P is swung from the position shown in dotted lines in Fig. 13 to the position shown in full lines in the same figure, so as to move the gage O a quarter of an inch away from the front ends of the signatures E. The operator now pushes the signatures E to the front until they abut with their ends on the gage O, and then the lever L⁴ is again swung downward to clamp the superimposed signatures in position on the carrier F. The above described sewing operation is then repeated, that is, the carrier F is moved rearwardly and the now superimposed signature is sewed onto the previously sewed uppermost signatures, the only difference being that the stitches pass through the uppermost signatures intermediate the previously made stitches. The several signatures are sewed together in the manner described, that is, the lowermost is removed at the end of each sewing operation and placed on the top of the signature until the series of signatures are sewed together, it being understood that after each full sewing operation the gage O and the signatures are shifted to stagger the stitches of succeeding signatures. When it is desired to sew a lining or a fly leaf E' to the first or last signature of the book, then such fly leaf E' is placed in position by the operator on the uppermost signature, as indicated in Fig. 8 with the fly leaves on opposite sides of the needle C and the back E² of the lining in contact with the uppermost signature intermediate the adjacent edge of

the clamping plate F⁴ and the presser foot Q. The above described sewing operation is then repeated to sew the back E² of the lining E' to the signature uppermost at the time. 70

From the foregoing it will be seen that by the arrangement described the uppermost signatures are fastened together by stitches passing slantingly through the said signatures and with the loops at the back of the 75 signatures so that the signatures are very securely fastened together to insure the formation of a strongly bound book, after the cover is attached in the usual manner. 80

It is understood that when the signatures E are of comparatively soft paper the hole punch I is dispensed with and the sewing needle C now makes its own hole through the uppermost signatures on the descent of the needle bar C. 85

It will be noticed that by arranging the presser foot Q to engage the uppermost signature directly at the back margin, the signatures are firmly held in place while the needle C passes through the uppermost signatures and while the stitch is formed at the back of the signatures so that the signatures are firmly sewed together and an effect is produced corresponding to hand overcast sewing and oversewing and whip-stitching. 90

Having thus described my invention, I claim as new and desire to secure by Letters Patent:

1. In a book sewing machine, the combination with a reciprocating sewing needle and coöperating stitch-forming mechanism, of a guideway having a fixed ledge at an acute angle to the line of travel of the sewing needle, and having a bottom approximately at a right angle to the said ledge, a signature carrier mounted to slide step by step on the said guideway and adapted to support superimposed signatures to be sewed together, the signatures having their backs abutting against the said ledge, a spring bar fixed on the said guideway bottom and provided with notches spaced equal distances apart, and a spring-pressed catch on the said signature carrier and adapted to successively engage the said notches. 100

2. In a book sewing machine, the combination with a reciprocating sewing needle and coöperating stitch-forming mechanism, of a guideway having a fixed ledge at an acute angle to the line of travel of the sewing needle, and having a bottom approximately at a right angle to the said ledge, a needle plate in the said ledge for the needle to pass through, a needle guide on the underside of the said ledge in alignment with the said needle plate and the stitch-forming mechanism to support the needle while the stitch is formed, and a signature carrier mounted to slide step by step on the said guideway 110

and adapted to support superimposed signatures to be sewed together, the signatures having their backs abutting against the said ledge.

5 3. In a hook sewing machine, the combination with a reciprocating sewing needle and coöperating stitch-forming mechanism, of a guideway having a fixed ledge at an acute angle to the line of travel of the sewing 10 needle, and having a bottom approximately at a right angle to the said ledge, a needle plate in the said ledge for the needle to pass through, a needle guide fixed on the under side of the ledge and having an eye and a 15 groove extending from the said eye for receiving the needle to guide the latter to the stitch-forming mechanism, and a signature carrier mounted to slide step by step on the said guideway and adapted to support superimposed signatures to be sewed together, 20 the signatures having their backs abutting against the said ledge.

4. In a book sewing machine, the combination with a reciprocating sewing needle and 25 coöperating stitch-forming mechanism, of a guideway having a fixed ledge at an acute angle to the line of travel of the sewing needle and having a bottom approximately at a right angle to the said ledge, a signature 30 carrier mounted to slide step by step on the said guideway and adapted to support superimposed signatures to be sewed together, the signatures having their backs abutting against the said ledge, and an adjustable

gage at one end of the said signature carrier to allow shifting of the superimposed signatures prior to starting a new row of 35 stitches.

5. In a book-sewing machine, the combination with a reciprocating sewing needle and 40 coöperating stitch-forming mechanism, of a guideway having a fixed ledge at an acute angle to the line of travel of the sewing needle, and having a bottom approximately at a right angle to the said ledge, a signature 45 carrier mounted to slide step by step on the said guideway and adapted to support superimposed signatures to be sewed together, the signatures having their backs abutting against the said ledge, a bar fixed 50 on the said guideway bottom and provided with notches spaced equal distances apart, a spring-pressed catch on the said signature carrier and adapted to successively engage the said notches, a gage mounted to slide 55 on one end of the said carrier, and means for shifting the said gage lengthwise of the carrier a distance corresponding to one half of the distance between adjacent notches in the said bar.

In testimony whereof I have signed my name to this specification in the presence of two subscribing witnesses.

FERDINAND GAILER.
